UNITED STATES PATENT OFFICE.

SWITS CONDÉ, OF OSWEGO, NEW YORK.

DESIGN FOR A KNIT FABRIC.

SPECIFICATION forming part of Design No. 12,763, dated February 14, 1882.

Application filed December 12, 1881. Term of patent 7 years.

To all whom it may concern:

Be it known that I, SWITS CONDÉ, of Oswego, in the county of Oswego, in the State of New York, have invented new and useful Improvements in Design for Knit Fabric, of which the following, taken in connection with the accompanying drawing, is a full, clear, and exact description.

The nature of this design consists in a novel combination and arrangement of stripes of different shades and widths, as illustrated in the annexed drawing, which represents a section of knitted fabric embodying my design.

a denotes a wide mottled stripe followed by a narrow plain light stripe, b, then a mottled stripe, c, of about one-third the width of the stripe a, then another narrow plain light stripe, b, then resuming with the first wide mottled stripe, a, and continuing as aforesaid, all of said stripes being arranged side by side in the order stated and straight and parallel, as shown.

What I claim is—

The design for knitted fabric, consisting of the wide mottled stripe a, followed by a narrow plain light stripe, b, then a mottled stripe, c, of about one-third the width of the stripe a, then another narrow plain light stripe, b, then resuming with the first wide mottled stripe, a, and continuing as aforesaid, all of said stripes being arranged side by side in the order stated and straight and parallel, as shown.

In testimony whereof I have signed my name and affixed my seal, in the presence of two attesting witnesses, at Oswego, in the county of Oswego, in the State of New York, this 1st day of November, 1881.
